UNITED STATES PATENT OFFICE.

WILLIAM A. DAY, OF BELLINGHAM, WASHINGTON, ASSIGNOR OF ONE-HALF TO
VICTOR I. BRADWAY, OF BELLINGHAM, WASHINGTON.

COMBINATION HAMMER AND NAIL-PULLER.

1,012,527.

Specification of Letters Patent.

Patented Dec. 19, 1911.

Application filed March 22, 1911. Serial No. 616,126.

To all whom it may concern

Be it known that I, WILLIAM A. DAY, a citizen of the United States, residing at Bellingham, in the county of Whatcom and 5 State of Washington, have invented new and useful Improvements in Combination Hammers and Nail-Pullers, of which the following is a specification.

An object of the invention is to provide a 10 hammer for driving nails and the like into material and provided with means for withdrawing nails from material.

To obtain the desired result, use is made 15 of a hammer head attached to a handle, a shoulder integrally formed on one side of the hammer and a toothed eccentric mounted on the hammer adjacent the said shoulder, so that when it is desired to remove a nail from a piece of material, the said nail is received 20 between the said shoulder and the said toothed eccentric, so that the eccentric will grip the nail, thus permitting of removing the same from the material by exerting a pull on the handle of the hammer.

25 Aside from performing the function of pulling nails and other securing members from material, my device embodies a hammer similar to the usual hammers now in use.

Reference is to be had to the accompanying 30 drawings constituting a part of this specification, in which similar characters of reference denote corresponding parts in all the views, and in which—

Figure 1 is a side elevation of my device 35 showing the same applied to a board to disengage a nail therefrom. Fig. 2 is a plan view. Fig. 3 is a section taken on the line 3—3 in Fig. 2.

Referring more particularly to the views, 40 I employ a hammer head 10 provided with an aperture 11 adapted to receive a handle 12, the said hammer head 10 having one end 13 thereof adapted for hammering and the other end 14 bifurcated to form a slot 15.

Formed on one side of the hammer head 10 45 is a shoulder 16 and adjacent the said shoulder a toothed eccentric 17 is revolvably mounted, the said eccentric being shaped like a wheel and turnable so that one side thereof can be moved immediately adjacent 50 the end of the shoulder 16.

In the application of my device when it is desired to withdraw a nail from a bar 18, as shown in Fig. 3, the protruding end of the nail is received between the shoulder 16 and 55 the eccentric 17 and the eccentric is then turned so that the teeth thereon will grip the nail, after which a pull is exerted on the hammer so that the nail will be withdrawn from the bar 18, the end 14 of the hammer 60 being adapted as a fulcrum when it is desired to withdraw the nail from the board.

It will be understood that aside from providing a nail puller, my hammer can be used 65 in the usual manner for hammering nails and the like into a material, and it will be further understood that the scope of the invention is defined in the appended claims.

Having thus fully described the invention, 70 what I claim as new, is:—

1. A device of the class described comprising a hammer head, a handle for the said hammer head, a shoulder integrally formed on the hammer head and an eccentric wheel 75 revolvably mounted on the hammer head adjacent the said shoulder.

2. A device of the class described comprising a hammer head provided with a handle, a shoulder on the hammer head and a toothed eccentric wheel revolvably mounted on the 80 said hammer head.

In testimony whereof I affix my signature in presence of two witnesses.

WILLIAM A. DAY.
